UNITED STATES PATENT OFFICE.

CHARLES HAZELTON O'CONNOR, OF SAULT STE. MARIE, ONTARIO, CANADA.

PAPER-BAG CONTAINER.

Application filed May 28, 1923. Serial No. 642,151.

To all whom it may concern:

Be it known that I, CHARLES H. O'CONNOR, a citizen of the United States, residing at Sault Ste. Marie, in the Province of Ontario and Dominion of Canada, have invented a new and useful Paper-Bag Container, of which the following is a specification.

This invention relates to a rack or container for paper bags, one of its objects being to provide a container in the form of a housing or casing adapted to be supported on a counter or the like and which has separate compartments for holding bags of different sizes where the closed ends or satchel portions can be readily reached for the purpose of removing a bag easily.

Another object is to provide a simple and efficient means for exerting a constant pressure on one end portion of a pack of bags, this pressure remaining substantially constant irrespective of the thickness of the pack.

Another object is to provide a structure which can be easily refilled.

With the foregoing and other objects in view which will appear as the description proceeds the invention consists of certain novel details of construction and combinations of parts which will be hereinafter more fully described and pointed out in the claim, it being understood that various changes may be made in the construction and arrangement of the parts without departing from the spirit of the invention as claimed.

In the accompanying drawings the preferred form of the invention has been shown.

In said drawings:

Figure 1 is a perspective view of the container showing bags in position to be withdrawn therefrom.

Figure 2 is a vertical section through the device.

Figure 3 is a rear elevation of one of the pressure devices.

Referring to the figures by characters of reference 1 designates a suitable housing preferably mounted on a base 2 and provided with an open back as shown particularly in Figure 2. Transverse downwardly and forwardly inclined supporting strips 3 are arranged within the housing and are interposed between vertical partitions 4 arranged within the housing. These partitions and the supporting strips thus form pockets 5

of different sizes, one pocket being employed for each pack of bags placed in the housing.

Formed in the front wall of the housing above but close to each of the strips 3 is an opening 6 extending throughout the width of the pocket. This opening is so located that when a folded bag is supported on end within a pocket the upper portion of the satchel bottom of the bag will be positioned where it can be grasped readily for the purpose of removing the bag through the opening. In the drawings the bags in the pockets have been indicated at B and the bottoms of the bags have been illustrated at B'.

Screw eyes or the like, shown at 7 are connected to the rear portions of the strips 3 and are preferably arranged in pairs. Each pair of eyes is engaged by one end of a frame 8 and pivotally connected to the other end of the frame are the arms of an elongated yoke 9, these arms having eyes 9' engaging the frame. A coiled spring 10 is mounted on each frame 8 between the eyes 7 and one end of the spring engages the adjacent strip 3 so as to be held against movement while the other end of the spring engages one side of the frame 8 so as to press the frame toward the closed front of the housing. Another coiled spring 11 is mounted on the other end of the frame 8 and one end of the spring bears against the frame while the other end of the spring bears against the yoke 9. Thus said yoke is normally pressed toward the closed front end of the housing. The yoke is so proportioned that the lower end thereof is directly back of the opening 6 of the pocket in which the yoke is mounted.

In loading or filling the container packs of bags of the different sizes to be used are placed within the respective pockets. The front of the housing may be provided with means adjacent the openings 6 for indicating the sizes of the bags located back of the openings. For example bags for holding half pounds are placed in the pocket the opening of which is indicated by the character "1" while bags for holding three pounds of material will be placed in the pocket the opening of which is designed by the numeral "3". Before the bags are placed in the pockets the frames 8 and yokes 9 are swung outwardly from the pockets to allow the packs of bags to be placed in the pockets. By then releasing the frames and

yokes they will be moved by their springs so as to press against the packs and force the bags against the front of the housing. To remove any one of the bags exposed 5 through the openings it is merely necessary to grasp the exposed portion B' and pull the bag through the opening. The novel pressure means in each pocket insures the clamping of all portions of the pack of bags against the front of the housing and the lower portion of the pack is at all times slightly buckled back of the opening 6 so as to insure the projection into the opening 10 of the portion B' of the front bag.

15. What is claimed is:

In a paper bag container, a housing having a pocket at the back thereof, said pocket having an outlet opening in its front near the bottom extending throughout the width 20 of the pocket, a frame hingedly mounted in the lower portion of each pocket and ex-

tending upwardly within the pocket, a spring for pressing the upper portion of the frame yieldingly toward the contents of the box, a yoke hingedly mounted on the 25 upper end of the frame and extending downwardly therefrom, a spring for holding all portions of the yoke normally pressed yieldingly against the contents of the pocket, substantially through the width and 30 length of said contents, the bottom of the pocket being inclined downwardly toward the front thereof, the free end of the yoke terminating back of the outlet opening in the pocket.

35 In testimony that I claim the foregoing as my own, I have hereto affixed my signature in the presence of two witnesses.

CHARLES HAZELTON O'CONNOR.
